Primary Examiner — W. A. Teddy Falloway*Assistant Examiner* — Amanda Kay Birdwell(74) *Attorney, Agent, or Firm* — RANKIN, HILL & CLARK LLP(57) **CLAIM**

The ornamental design for a lid for a bottle, as shown and described.

DESCRIPTION

FIG. 1 is a perspective view of a lid for a bottle showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1; and,

FIG. 8 is a perspective view of FIG. 1.

The broken lines in the drawings depict portions of the lid for a bottle that form no part of the claimed design.
